J. GROSS

BRIDGE SIGNAL FOR RAILROADS

Filed Jan. 6, 1925

Fig. 2.

Inventor
Joseph Gross.

By *A. J. O'Brien*
Attorney

UNITED STATES PATENT OFFICE.

JOSEPH GROSS, OF DENVER, COLORADO.

BRIDGE SIGNAL FOR RAILROADS.

Application filed January 6, 1925. Serial No. 755.

To all whom it may concern:

Be it known that I, JOSEPH GROSS, a citizen of the United States, residing at Denver, in the city and county of Denver and State 5 of Colorado, have invented certain new and useful Improvements in Bridge Signals for Railroads; and I do declare the following to be a full, clear, and exact description of the invention, such as will enable others 10 skilled in the art to which it appertains to make and use the same, reference being had to the accompanying drawings, and to the characters of reference marked thereon which form a part of this specification.

15 This invention relates to improvements in bridge signals for railroads.

The railroads employ in their construction, a large number of bridges of different type, the smaller of which are of the trestle 20 type of construction. Many of the smaller bridges span creeks or dry ditches that are subject to sudden and great variations in the flow of water. It often happens that 25 after a storm or during the spring thaw a small creek or a dry ditch becomes a raging torrent that sometimes washes away the ground about the bridge foundations to such an extent that the bridge becomes unsafe.

It is the object of this invention to produce 30 a signal device of simple and substantial construction that can readily be applied to any existing bridge and which will cause a danger signal to be set if the foundations of the bridge have been damaged to 35 such an extent that the bridge has become unsafe.

My invention briefly described consists in embedding in the ground, adjacent the spiles or supporting walls, a member that will be 40 moved by the water whenever it shall be uncovered and which is provided with means for operating a signal when it is moved.

In order more clearly to describe my invention, I have illustrated one embodiment 45 thereof, which I will now describe in detail, reference for this purpose being had to the accompanying drawing in which—

Fig. 1 is a side elevation of a bridge of trestle construction.

50 Fig. 2 is a partial section taken on line 2—2.

Fig. 3 is a fragmentary view showing a side elevation of the switch and a diagram of connections, and

Fig. 4 is a section taken on line 4—4 55 Fig. 3.

In Fig. 1 I have shown a side elevation of a bridge trestle construction; numeral 1 indicates the rails, 2 the ties, 3 the signals and 4 the spiles. The specific construction 60 of the bridge is immaterial and I will, therefore, refrain from describing the same in detail, except, in so far as it may be desirable to do so in order to explain my invention. 65

The spiles 4 are usually arranged in groups which I have designated as A, B, C, D and E. Each group consists of several piles arranged somewhat as shown in Fig. 2 with their lower ends sunk into the 70 ground to a considerable depth. If the water should wash away the ground from about the lower ends of the spiles, the bridge would, of course, become unsafe. As pointed out above, it is the object of this invention to produce a signal operating means 75 which will cause the danger signals at each end of the bridge to become operative, if the bridge has become undermined to such an extent as to become dangerous. In order 80 to accomplish the object I take a piece of timber such as a two by four 5 and drive one end thereof into the ground along side of one or more of the spiles of each group in the manner shown in Figs. 1 and 2. The 85 timber 5 is driven into the ground to the depth to which the ground must be washed away before the bridge becomes dangerous.

The upper end of the timber 5 has a short length 6 separated from it and secured to 90 the spile by lag screws 7. The parts 5 and 6 are connected by a hinge 8. An eye bolt 9 is fastened to each of members 5 and 6. The eyes of these bolts are connected by a 95 spring 10 which is under tension and which therefore tends to swing the part 5 into dotted line position (Fig. 2). The members 5 and 6 are secured to the spiles in such 100 a manner that the water as it flows past tends to move the part 5 into dotted line position (Fig. 2). If the ground is washed away to a depth indicated by the dotted line 11 in Fig. 2 the part 5 becomes free to 105 swing about the hinge pin and the action of the water and the spring 10 will cause the same to assume a position somewhat as shown in dotted lines in Fig. 2. Whenever this occurs, the signals 3 must be made oper-

ative and set to danger. I accomplish this by the following means. To the part 6 I fasten an insulating base 12 to which is secured the switch contact 13. A switch blade 14 is pivotally connected to contact 13 at 15. A compression spring 16 extends between the base 12 and the switch blade 14 and tends to move the blade to the dotted line position (Fig. 3). Secured to the upper end of member 5 is an insulating base member 17, to which the switch contact 18 is connected. This switch contact is formed with two spaced sides 19, whose ends 20 are bent inwardly in the manner shown in Fig. 4 to such an extent that they prevent the blade 14 from being moved out by the action of the spring 16. When the parts 5 and 6 are aligned in the manner shown in Figs. 2 and 3, the switch blade makes electrical connection between the contacts 13 and 18, but when the part 5 swings to dotted line position (Fig. 2) the blade 14 will be withdrawn from the contact 18 so as to break the electrical connection. The spring 16 moves the blade to this dotted line position (Fig. 3) and prevents the switch from closing if the member 5 should accidentally swing back to full line position. The switch blade and spring 16 may, if desired, be replaced by a wire that will be broken when the parts 13 and 18 move apart. The switch just described is located in a closed circuit formed by wires 21, 22, 23 and battery 24 when the circuit is closed the magnet 25 is energized, but as soon as the circuit is open the magnet 25 is deenergized and releases an armature 26 which closes a local circuit and causes the semaphore 27 to be moved to danger position. Any other signal operating means may be employed that is adapted to be set into operation by my circuit opener.

In the drawings, I have shown my device applied to one spile only of each group, but it is obvious that as many of these devices may be applied as may be deemed necessary. It is, of course, necessary to connect all of the circuit openers in series so that the signal will be operated whenever any one of them operates.

Although I have referred to members 5 and 6 as being constructed of wood, this is, of course, not necessary as they may be made of old boiler tubing, channel or angle irons, or any other suitable material.

Having now described my invention, what I claim as new is:

1. In a bridge signal, in combination, a bridge having supports, a member fastened to each support, a second member hingedly connected to the first member and normally aligned therewith, said second member having one end extending into the ground adjacent the support with which it is associated, switch means operatively associated with said members, said switch means being formed in two parts, one of which is associated with each of said members, said switch being adapted to open when the said members move out of alignment and a signal adapted to be moved to operative position when the switch is opened.

2. A bridge signal comprising, in combination, a member adapted to be secured to a part of the bridge structure, a second member hingedly connected to the first mentioned member and adapted to occupy a position in alignment therewith, a switch having two contacts, one of which is connected to each of said members, means for connecting the contacts electrically when the members are in aligned position and for disconnecting said contact when the members are moved out of alignment, a signal and means for making the signal operative when the switch opens.

3. A bridge signal comprising a bridge support having one end extending into the ground, a switch operating device operatively associated with said support, said device having one part rigidly secured to the support and a second part having its upper end hingedly connected to the first part, the lower end of the second part being embedded in the ground adjacent the support so as to be held against movement by means of the ground, a switch having two contacts one of which is connected to each of said parts means for electrically connecting the switch contacts, while the parts occupy normal position, said connecting means being adapted to disconnect said contacts when the parts move from normal position, a signal and means for causing said signal to become operative when the contacts are disconnected.

In testimony whereof I affix my signature.

JOSEPH GROSS.
